UNITED STATES PATENT OFFICE

106,971

DESIGN FOR A BOWL OR SIMILAR ARTICLE OF HOLLOW WARE

George Thornton Gilby, Brighton, England, assignor to The Wallingford Company, Incorporated, Wallingford, Conn., a corporation of Connecticut

Application September 22, 1937, Serial No. 71,718

Term of patent 14 years

To all whom it may concern:

Be it known that I, George T. Gilby, a subject of Great Britain, residing at Brighton, in the county of Sussex, England, have invented a new, original, and ornamental Design for a Bowl or Similar Article of Hollow Ware, of which the following is a specification, reference being had to the accompanying drawing, forming part thereof.

Fig. 1 is a side view illustrating a bowl or similar article of hollow ware for table service showing my design;

Fig. 2 is a sectional view on the line 2—2 of Fig. 1; and

Fig. 3 is a sectional view on the line 3—3 of Fig. 1.

The bowl shown is of conventional oval contour and the ornamentation is continued throughout the surface of the bowl. The characteristic feature of the design resides in plurality of flutes projecting outwardly from the body of the bowl or similar article, substantially as shown.

I claim:

The ornamental design for a bowl or similar article of hollow ware substantially as shown and described.

GEORGE T. GILBY.
